UNITED STATES PATENT OFFICE.

SAM A. SHAPIRO, OF NEW YORK, N. Y., ASSIGNOR, BY MESNE ASSIGNMENTS, TO
ARTHUR DORSEY, OF NEW YORK, N. Y.

ILLUMINATED DIAL CONTROL.

Application filed December 20, 1926. Serial No. 155,987.

This invention relates to illuminated dial controls for radio apparatus and the like purposes.

An object of the invention is to provide an illuminated dial control of improved practical construction, particularly adapted for use with tuning units of radio and the like apparatus.

Another object of the invention is to provide a control for radio tuning devices of the character described in which a translucent dial illuminated from the rear side thereof is mounted with the tuning device on the rear side of the panel and operated from the front side thereof, and simple means provided for viewing the dial in such manner that the control with the exception of its operating knob is for the most part concealed from view.

A further object of the invention is to provide an improved dial control of the character described in the form of a compact unit adapted to be mounted on the shaft of a tuning device on the rear of the control panel and having a vernier mechanism and electrically illuminating means for the dial.

A still further object of the invention is to provide a device of the character described which comprises few and simple parts, which may be easily assembled into a compact, rugged unit adapted to be readily installed on the radio panel and which shall be comparatively cheap to manufacture, neat in appearance, and efficient in operation to a high degree.

Other objects of this invention will in part be obvious and in part hereinafter pointed out.

In a co-pending application, Serial No. 155,968, filed Dec. 20, 1926, I have shown and described an illuminated dial control like that herein described and shown in the drawing but said co-pending application is directed particularly to attachment or coupling plates for connecting the tuning unit to the dial control. The present application, however, is directed mainly to the illuminating means and the dial control mechanism and accordingly no claim is made herein for the attachment or coupling plate, the latter being claimed in my said co-pending application.

With the above exception, the invention accordingly consists in the features of construction, combinations of elements, and ar-

angement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view showing an improved illuminated vernier dial control embodying the invention installed to interconnect with an adjustable condenser, parts of said control being broken away to show the construction thereof.

Fig. 2 is a rear elevational view of the control as seen from a cut taken on line 2-2 in Fig. 1.

Fig. 3 is a front elevational view of the improved dial control dismounted from the panel.

Referring in detail to the drawing, 10 denotes a front panel of a radio set which has mounted on the rear side thereof an illuminated dial control 11 embodying the invention adapted to operate a tuning device, such as an adjustable condenser 12. As here shown, the dial control 11 is electrically lighted and is of the vernier type, said control being mounted for turning the shaft 12^a of the condenser 12 at a comparatively slow speed relative to the speed of a manually operated knob 13.

The control knob 13 has a set screw 14 which secures it to the front end of a horizontally extending drive shaft 15 journaled in a sleeve bearing 16 which has its front threaded end 16^a extended through an opening 10^a provided in the front panel 10. Said threaded end 16^a has a clamping nut 17 for rigidly securing the sleeve bearing to the panel, and serves as the main mounting for the control.

Rigidly fastened to the outside of the sleeve bearing 16 adjacent the inner end 16^b and extending vertically upward, is an elongated frame bar 18. A mid-portion of said bar rotatably supports the rear end 19^a of a hollow shaft 19 so that the latter extends in parallel alignment with said bearing 16. Said shaft 19 is adapted to couple with the shaft end 12^a for turning the condenser rotor electrode 12^b to adjust the capacity of the condenser. The shaft end 12^a is secured so as to turn with the hollow shaft 19 by means of a set screw 20 threaded into the latter.

- A frictional gear member 21 is secured to extend down from the hollow shaft 19 in front of the frame bar 18 and is adapted to engage with a drive wheel 22 mounted on the rear end of the shaft 15. The gear member 21 is preferably formed of a pair of discs 23 which are secured together by means of rivets 24 spaced adjacent the periphery of said member as shown in Figs. 1 and 2.
- 10 Said member 21 has an arcuately shaped opening 21^a extending through the mid-portion thereof, the outer rim edge 21^b of said opening being concentrically curved with respect to the axis of rotation of the mounting of said member 21 on the hollow shaft 19.

As will be seen from Fig. 1, the drive wheel 22 has a peripheral portion 22^a of V-shaped cross section which is inserted between the plates 23 at said rim edge 21^b and 20 serves as a wedge to form a spring frictional internal gearing drive. The opening 21^a is shaped to accommodate the rear sleeve bearing end 16^b, the latter being slotted at 16^c to permit unobstructed cooperation between the 25 drive wheel 22 with the gear member 21. The ends of the opening 21^a serve as stops for limiting the rotation of the member 21 and hollow shaft 19 preferably to half a revolution for permitting the adjustment of the 30 condenser from maximum to minimum capacity in the well understood manner.

Extending upwardly from the front end of the hollow shaft 19 and firmly secured thereto by means of a clamping nut 25 is a 35 carrier plate 26 to the peripheral portion of which is secured a semi-circular graduated dial 23 positioned adjacent the rear side of the panel 10. Said dial may be made of any translucent material, such as celluloid, 40 glass or other suitable substance and may be attached to the carrier plate 26 in any suitable manner as by cementing or by means of rivets 27, as shown. For observing the dial from the front of the panel, an opening 45 10^b is provided in the panel 10. Said opening has fitted therein a window frame 29 which may be of any suitable construction, and may, for example, be made of stamped sheet metal formed with a frame portion 29^a 50 which extends through and about the front rim of the opening 10^b and has rearwardly extending prongs 29^b for engaging a transparent sheet 29^c forming a closure for said opening, as is clearly shown in Fig. 1. A 55 suitable marker in the form of a vertically extending cross wire 30 may be provided in the window to facilitate reading the dial setting.

For illuminating the dial from the rear 60 side thereof, a miniature electric bulb 31 is dependingly carried in the shell socket 32 which is suitably insulated and mounted on a bent horizontally extending portion 18^a of the frame bar 18. Said socket 32 is connected to a suitable power source (not

shown) and preferably has a suitable control switch 33 in circuit therewith. As here shown, said switch 33 may be of the "push and pull" type and comprises a threaded body portion 33^a which is firmly secured to the upper vertical end 18^b of the frame member 18^a and extends through an opening 10^c provided in the panel 10. Said threaded body portion 33^a has a nut 34 mounted on the front end thereof for clamping the panel 10 and anchoring the upper end of the frame bar 18 in position to the rear side of said panel. Said switch body portion carries a reciprocating plunger 35, the front end of which is provided with a finger-piece 35^a, the rear end thereof having a tapered insulating head 35^b. The latter cooperates with a projecting end 36^a of a spring blade 36 secured to the frame bar 18 on an insulating support 37 by means of screws 38, as is clearly shown in Fig. 1. For connecting the lamp and switch in circuit with the power source, terminal posts 39 and 40 are provided connecting with the spring blade 36 and the socket 32, respectively. It is apparent that when the switch parts are positioned as shown in Fig. 1, the lamp circuit is open and on pulling the switch plunger 35 forward the insulating head depresses the blade and brings the latter into contact with the center terminal 31^a of the lamp 31, thus closing the circuit for lighting the lamp.

The frame or stator of the condenser 12 is fixedly secured in position to the frame bar 18 by an interconnecting attachment or coupling plate 41 which carries an adjustable pin 42 whereof a forwardly projecting end 42^a engages in an elongated slot 18^c provided in the frame bar 18. Where the condenser 12 is constructed for "one-hole" mounting and is provided with a supporting disc 43 on the bearing of the shaft 12^a of the rotor electrode, as shown in Fig. 1, said plate has one end portion thereof firmly clamped against the disc 43 by means of a nut 44 and is provided with a clearance opening 41^a through which said condenser shaft 12^a freely passes. The opening 41^a may be made sufficiently large to accommodate the various commercial sizes of condenser shafts. Said plate 41 also has an elongated slot 41^b extending centrally therethrough which is adapted to permit adjustment of the pin 42 therein, the latter being mounted on the plate 41 in any suitable manner, as by means of the lock nuts 45. The construction described above including the plate 41 permits the securing of the stator of the condenser 12 in any angular position relative to the bar 18 and the panel 10 by adjusting the pin 42 between the slots 41^b and 18^c of the plate 41 and the member 18, respectively. To prevent possible loose engagement between the pin end 42^a in the 120

slot 18^c, the outer surface of said pin end may be knurled with raised surface projections to afford a simple forced fit of the pin end 42^a in the slot 18^c. It should be noted that the interconnecting means between the relatively fixed parts of the condenser and the dial control through the plate 41 is of a very simple construction and is effective to a high degree in forming a rigid structure which may be adjusted for coupling standard "one-hole" mounting condensers in any desired angle position relative to said dial control.

The operation of the device will now be clear. The control is installed and connected in circuit with the parts disposed as shown in the drawing, and the bulb 31 is lighted for illuminating the dial 28 by pulling the plunger 35 forward. The dial graduations 28^a which occupy a semi-circular section may be observed through the transparent window closure 29^c. The condenser 12 may be adjusted by turning the knob 13 for rotating the wheel 22 which engages with the frictional gear 21, the latter being effective to turn the hollow shaft 19 together with the condenser rotor 12^a secured to rotate therewith. The rotation of the hollow shaft carries the dial past the window so that any setting of the condenser may be determined by noting the graduation 28^a at the cross-wire or marker 30 in the usual manner. Terminating each end of the graduations 28^a on the dial, there may be provided an indicia 46 preferably of a color contrasting with that of the dial background and the graduations so as to indicate the maximum and minimum range of the device. For example, where the dial is white and the graduation black, said indicia 46 may be red.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A device of the character described comprising a panel, and control means adapted to operate a tuning device mounted on the rear side of the panel, said means including a drive shaft extending through the panel adapted to be manipulated from the front side thereof, a dial mounted at the rear of the panel and adapted to move with said device, and a light for the dial mounted at the

rear of the panel, said panel having a window for observing the dial from the front of the panel.

2. A control means of the character described including a member adapted to support said control means on the rear side of a panel, coupling means journaled in said member, one end of said coupling member being adapted to engage with a radio tuning device, a dial carried at the other end of said coupling means, a light secured to said member for illuminating the dial, and means for turning said coupling means and dial adapted to be manipulated from the front side of the panel.

3. A control means of the character described including a member adapted to support said control means on the rear side of a panel, coupling means journaled in said member, one end of said coupling means being adapted to engage with a radio tuning device, a translucent dial carried at the other end of said coupling means, an electric light secured to said member for illuminating the dial from the rear side thereof, and means for turning said coupling means and dial, said turning means adapted to extend through the panel and serve to rigidly secure the control means to the latter.

4. A control means of the character described including a member adapted to support said control means on the rear side of a panel, coupling means journaled in said member, one end of said coupling means being adapted to engage with a radio tuning device, a translucent dial carried on the other end of said coupling means, an electric light secured to said member for illuminating the dial from the rear side thereof, turning means on one end of said member for rotating said coupling means and dial, and a switch for the electric light on the other end of said member, said turning means and switch extending through the panel and serving to rigidly secure the control means to the latter.

5. A device of the character described comprising a panel, control means adapted to operate a tuning device mounted on the rear side of the panel, a drive shaft for said control means extending through the panel adapted to be manipulated from the front side thereof, said control means including a dial having graduations adapted to move with said device, and a light for the dial, said panel having a window for observing the dial from the front side of the panel, said dial having indicia extending beyond the graduations for indicating in the window the extreme limits of movement of said control means.

6. In a control means of the character described adapted to operate a radio tuning device mounted on the rear side of a panel, a translucent dial having graduations

mounted to move with the tuning device, and an electric light positioned behind the dial for illuminating the latter, said dial having indicia extending beyond the graduations for indicating the extreme limits of movement of said control means.

7. A device of the character described comprising a panel and a control means adapted to operate a tuning device mounted on the rear side of the panel, said means including a reducing gear drive having a shaft extending through the panel adapted to be manipulated from the front side thereof, a dial adapted to be moved with said device, and a light for the dial, said panel having a window for observing the dial from the front of the panel.

8. A device of the character described comprising a panel and control means adapted to operate a tuning device mounted on the rear side of the panel, said means including a reducing gear drive having a shaft extending through the panel adapted to be manipulated from the front side thereof, a dial, an electric light for the dial, and a switch extending through the panel for controlling said light from the front side thereof, said panel having a window for observing the dial from the front side of the panel.

9. A control means of the character described including a member adapted to support said control means on the rear side of a panel, coupling means journaled in said member, one end of the coupling means be-

ing adapted to engage with a radio tuning device, a dial carried on the other end of said coupling means, a light secured to the member for illuminating said dial, and a vernier drive engaging with said coupling means having an operating shaft extending through the panel adapted to be manipulated from the front side thereof for rotating said coupling means and said dial at a reduced speed.

10. A control means of the character described including a member adapted to support said control means on the rear side of the panel, coupling means revolvably supported by said member, one of said coupling means being adapted to engage with a radio tuning device, a translucent dial carried on the other end of said coupling means, an electric light secured to said member for illuminating the dial from the rear side thereof, a vernier drive engaging with said coupling means having an operating shaft extending through the panel adapted to be manipulated from the front side thereof for rotating the coupling means and dial at a reduced rate of speed, a journal bearing on one end of said member for said shaft, and a switch for the electric light on the other end of said member, said bearing and switch extending through the panel and serving to rigidly secure the control means to the latter.

In testimony whereof I affix my signature.

SAM A. SHAPIRO.
